UNITED STATES PATENT OFFICE.

RUDOLPH CONRADER, OF ERIE, PENNSYLVANIA.

PUMP-CONTROLLING MECHANISM.

Application filed February 21, 1922. Serial No. 538,207.

To all whom it may concern:

Be it known that I, RUDOLPH CONRADER, a citizen of the United States, residing at Erie, in the county of Erie and State of Pennsylvania, have invented new and useful Improvements in Pump-Controlling Mechanism, of which the following is a specification.

This invention is designed to economically and efficiently control compressors and pumps to adjust them to variations in the output desired. In its preferred form the invention relates to a compound compressor or pump. In carrying out the invention the capacity is stepped up or down by cutting out separate units. As exemplified the invention is shown as a compressor having a high and low pressure cylinder and one end of the high pressure and one end of the low pressure cylinder are first unloaded. Then the opposite ends of the high and low pressure cylinder are unloaded. This is accomplished in the present invention leaving the pressure in the usual intercooler unchanged so that there is no loss through this source as the pumps or compressors are unloaded. I preferably effect the unloading by closing off the inlet and preferably supply relief valves for exhausting the cylinders after the inlet valves are closed. This is of importance with an intercooler because any leakage of the inlet valves would be carried to the intercooler so that there would not only be loss of economy by reason of the leak of the inlet valves but also the danger as to over-loading the intercooler. In controlling the stepped unloaders I prefer to provide plural regulators, one of such regulators unloading one end of a pump and at the same time throwing the controlling pressure on to the second unloader so that the sequence in the action of the unloaders is assured. I further prefer to provide a means whereby the compressor, or pump, is positively unloaded regardless of the receiver pressure at the starting of the pump so that the motor which drives the pump can get under motion without the resistance of a load. This of particular importance in motors exerting their full power only when running at speed. The invention also involves other features which will be particularly described and pointed out in the claims.

The invention is illustrated in the accompanying drawings as follows:

Fig. 1 shows a side elevation of a compressor.

Fig. 2 an end view of the same.

Fig. 3 a plan view, slightly enlarged.

Fig. 3^a a plan view of a pipe connection.

Fig. 3^b a side elevation of an electric controlling switch.

Fig. 4 a sectional view on the line 4—4 in Fig. 5 of one of the unloaders.

Fig. 5 a section on the line 5—5 in Fig. 4.

Fig. 6 a section on the line 6—6 in Fig. 5.

Fig. 7 a side elevation, partly in section, of the regulator unloading the first end of the cylinders.

Fig. 8 a section on the line 8—8 in Fig. 7.

Fig. 9 a side elevation, partly in section, of the regulator controlling the unloading of the second ends of the cylinders.

Fig. 10 a section on the line 10—10 in Fig. 9.

Fig. 11 a side elevation, partly in section, on the line 11—11 in Fig. 12.

Fig. 12 a section on the line 12—12 in Fig. 11.

Fig. 13 a side elevation, partly in section, of the low pressure cylinder.

Fig. 14 a similar view of the high pressure cylinder.

Fig. 15 a front elevation of the controlling rheostat and a sectional view of the controlling mechanism for unloading the compressors at the starting of the motor.

Fig. 16 a section on the line 16—16 in Fig. 15.

Fig. 17 an elevation of a spring for actuating the rheostat lever.

1 marks the low pressure cylinder, 2 the high pressure cylinder, 3 the intercooler between the cylinders, 4 an electric motor driving the compressor through the usual crank shaft and connecting parts (not shown), 5 the frame of the compressor, 6 the bed on which it is mounted, 7 the piston rod, 8 the piston operating in the low pressure cylinder, 9 intake valves of any ordinary construction, 10 discharge valves, 11 and 12 intake passages, these passages being separated by a wall 13, and 14 a face plate leading to the passages 11 and 12, the face plate having a closure face 15 corresponding to the partition 13. The purpose of thus dividing the intake is to permit of separate unloaders for the opposite ends of the cylinders. The

unloader for the low pressure cylinder has a body 16, a face 16^a corresponding to the face 14, and passages 17 and 18 leading to the intakes 11 and 12, valve openings 19 and 20 controlling the passages 17 and 18, and a passage 21 into which both valve openings 19 lead. A pipe 22 leads to the intake from any desired source. Where air is being compressed this may open direct to the atmosphere. Valves 23 control the openings 19 and 20. These have the stems 24 which lead to pistons 25. The pistons are arranged in cylinders 26 secured to the body 16 and have the inlet openings 27 with which the pipes leading from the regulators are connected. The discharge valves 10 lead to the usual discharge passage 30 and this is connected by a pipe 31 with an inter-cooler 3. A pipe 32 leads from the inter-cooler to the unloader 33. This unloader is exactly similar in construction to that shown in Figs. 4, 5 and 6 and has the two controlled passages 33^a and 33^b leading to the inlet passages 34 and 34^a, these being separated by a partition 34^b and for the same reason as the partition 13 in the low pressure cylinder. Inlet valves 35 and 36 operate in the usual manner from the passages 34 and 34^a and a piston 38 is driven by the piston rod 37 as part of the linkage to the motor. Discharge valves 39 and 40 are provided, these leading to a discharge passage 41 and the discharge passage 41 leads to a pipe 42 which is the final discharge from the pump or compressor. Relief valves 43, 44, 45 and 46 are provided for the ends 1^a, 1^b, 2^a and 2^b respectively and in the contemplated operation these are automatically opened as the unloaders for the several ends operate. These relief valves are all the same in their detail construction and that construction is more particularly shown in Figs. 11 and 12. A body 47 has the screw-threaded end 48 which is secured in the end of the cylinder bringing the passage 49 into communication with the end of the cylinder. A valve opening 50 leads from the passage 49 and this is controlled by a valve 51. The valve 51 is guided in a cylinder 52 and a very light spring 53 tends to hold the valve in closed position, this valve acting during its relief operation as a check valve. A discharge passage 54 leads from the cylinder 52 and a pipe 55 leads from this discharge passage to the atmosphere or to some point of discharge—in a liquid pump ordinarily to the intake. The spring 53 is tensioned against a fitting 56. A push pin 57 extends through a gland 58 carried by the fitting 56 in position to engage the valve 51 and hold the same in closed position. A flange 59 extends from the fitting 56. This rests on the cylinder 52 and a cylinder 60 is mounted on top of the flange 59 and secured in place by screws 61. The push pin 57 has a shoul-

der 62 with a screw-threaded extension 63. A cup 64 is placed over the shoulder 62 and is clamped against the shoulder by a nut 65 arranged on the screw-threaded end 63. A spring 66 of sufficient strength to hold the valve 51 closed against the compression of the cylinder is provided and operates against the end of the stem 57, the pressure of this spring being adjustable by means of a plug 67 in the end of the cylinder 60. An inlet pipe 68 leads to the cylinder 60 and air or fluid under pressure is admitted to this cylinder whenever the corresponding unloader is put into action and this pressure acting under the plunger formed by the cup 64 lifts the push pin 57 against the spring 66 and relieves the valve 51 of its pressure. The valve then readily opens as a check valve until the pressure in the cylinder is exhausted. Inasmuch as the inlet is closed the piston will then operate so far as this particular end of the cylinder is concerned in a partial vacuum. Two of the unloaders and the relief valves corresponding thereto are operated from one regulating valve. In the present instance the ends 1^a and 2^a are coupled together so as to distribute the load to the opposite ends of the cylinders. The regulator controlling these unloaders and relief valves is shown in Figs. 7 and 8. A body 69 has a control connection 70 leading to a pipe 71. This pipe 71 leads to a side opening cross 72 and a pipe 73 leads from this cross to the unloader controlling the end 1^a. A branch pipe 74 leads from the pipe 73 to the relief valve 43. A pipe 75 leads from the cross 72 to the relief valve 45 and a branch pipe 76 leads from the pipe 75 to the unloader controlling the passage 33^a and consequently the end 2^a. A pipe 77 leads from the receiver (not shown) or from a part having receiver pressure as the pipe 42. This leads to the inlet opening 77^a in the body 69 and this opening leads to a port 78. The port 78 is in register with a passage 79 in a diaphragm case 81 and leads to a diaphragm chamber 80. A diaphragm 82 is mounted on the case 81 and clamped in position by a cover plate 83. A diaphragm button 84 engages a lever 85. The lever 85 is pivoted at 86 on an extension 83^a on the cover plate 83. A spring 87 rests on a head 88 which exerts pressure on the lever 85 opposite the button 84 and the opposite end of the spring rests against an adjusting screw 89 by means of which the tension of the spring may be adjusted so as to give a counter-pressure desired so that the predetermined pressure must be delivered to the diaphragm in order to actuate the mechanism to unload one end of the compressors. The lever 85 is connected by a link 90 with a bell crank lever 91. The bell crank lever 91 is pivoted on the case 81 by means of a pin 92. One arm of the bell crank lever en-

gages a yoke 93, this yoke being guided by the body 69. The yoke has the arms 94 which engage cross heads 95. The cross heads are drawn toward each other by 5 springs 96 which extend from the cross heads to ears 97 on the body. The cross heads are secured to stems 98 by nuts 99. A valve 100 controls the opening from the passage or port 78 to a port 101. The port 101 leads 10 to an axial port 102 which communicates with the discharge opening or end 70. An exhaust valve 103 controls a passage 104 leading from the port 102. The passage 104 connects with a port 105. This port is connected with a discharge opening 106 from which an exhaust pipe 107 leads to the starting mechanism hereinafter described.

It will be observed that both valves are closed as shown in the drawings but it will be understood that this condition of the valves is only momentary. The end of the lever 85 is provided with a V-shaped cam 85^a which engages a similar cam 85^b on the lever 85^c. The lever 85^c is pivoted on the case at 85^d and a spring 85^e operates against the lever 85^c. It will readily be seen that this cam action resists a movement of the lever 85 in either direction up to an intermediate or neutral point when the points of the 30 cams pass each other and from that on assists the movement. The effect of this is to prevent frequent reversals of the mechanism in that a pressure which will move the lever 85 against the action of the cams must be 35 reduced below such pressure before the counter-pressure device can return the mechanism against the pressure plus the resistance of the spring 85^e. The valves, therefore, are both closed only momentarily 40 and as the yoke 93 is moved in one direction, or the other, away from the cross heads 95 the springs 96 maintain the closure of the valve which is released by the movement of the feet or arms 94.

45 In the operation of the device when the pressure under the diaphragm rises above the pre-determined pressure the lever 85 is lifted and through the linkage heretofore described the valve 100 is opened permitting 50 the receiver air to pass to the pipe 71 and thus to the unloaders controlling the ends 1^a and 2^a and to the relief valves 43 and 45. Thus both these ends of the cylinders are 55 unloaded and what air there is in the cylinders is unloaded. The pump then continues through the opposite ends of the cylinders through the intercooler in the usual manner. Broadly this regulator forms the subject matter of application #519,163 filed by 60 me Dec. 1st, 1921, pressure controlled valve mechanism.

As the air or fluid is carried into the unloaders for these ends of the cylinders it is at the same time turned into the second 65 regulator. This regulator is shown in de-

tail in Figs. 9 and 10 and the air is delivered to this regulator through the pipe 71 and cross 72 which communicates through a pipe 108 leading from the port 101 to the inlet opening 109 in the body 110 70 of the second regulator. The opening 109 communicates with a port 111 and this port registers with a passage 112 leading to the diaphragm chamber 113 formed by the diaphragm case 114. A diaphragm 115 rests 75 on the edges of the case and is clamped in position by a cover plate 116. A button 117 communicates the movement of the diaphragm to the lever 118. The lever 118 is pivoted on a pin 119 mounted in an extension 80 116^a extending from the cover plate. A spring 120 rests on a head 121 which in turn engages the lever 118. This spring rests against a screw 122 by means of which the force of the spring may be adjusted to 85 the pressure which may be determined for the final unloading pressure of the pump or compressor. The lever 118 is connected by a link 123 with a bell crank lever 124, the bell crank lever being pivoted at 125. One 90 arm of the bell crank lever engages a yoke 126, the yoke being guided by the body 110. The yoke has arms 127 which engage the cross heads 128. These cross heads are drawn inwardly by springs 129 extending 95 from the cross heads to ears 130. Stems 131 are secured to the cross heads 128 by nuts 132. A valve 133 controls an opening between the port 111 and a passage 134. The passage 134 leads to a port 135 and this 100 leads to a discharge opening 136 through which a pipe 137 leads to the unloader controlling the end 1^b of the low pressure cylinder and a branch pipe 137^a leads to the relief valve 44 for the same end of the low 105 pressure cylinder. A pipe 138 leads from the pipe 137 to the unloader controlling the end 2^b of the cylinder 2 and a branch pipe 139 leads from the pipe 138 to the relief valve 46 on the same end of the high pressure cylinder.

This regulator is provided with mechanism for preventing frequent reversals in the same manner as the first regulator described. The lever 118 has a V cam 118^a 115 operating in connection with the cam 118^b. The cam 118^b is mounted on a lever 118^c and this is pivoted on a pin 118^d carried by the shell 114. A spring 118^e operates against the lever 118 and gives it the desired pressure to make the difference between reversals anything desired.

The regulator operates substantially in the manner of the regulator heretofore described. When the pressure under the diaphragm reaches the final pre-determined pressure for the compressor the upward movement of the diaphragm acting through the mechanisms referred to opens the inlet valve 133, this putting air under pressure 125

to the unloaders and relief valves so that the entire compressor is then unloaded. The regulator is provided with an exhaust valve 140 which controls the connection between the port 134 and a port 141. The port 141 leads to a discharge opening 142 and a pipe 143 leads from this opening connecting by means of a tee from the pipe 107 with a pipe 144, this leading to the starting control.

10 When the pressure reduces below the final predetermined pressure the spring 120 forcing down the lever 118 moves the yoke 126 so as to close the inlet valve 133 and open the exhaust valve 140. Immediately, therefore, the relief valves 44 and 46 close under the influence of their springs and the unloaders controlling the ends 1^b and 2^b of the low and high pressure cylinders are opened so that the pumping is resumed by these 20 cylinders. With another step in the drop of the pressure the first regulator operates to close the inlet valve 100 and to open the exhaust valve 103 so as to close the remaining relief valves and open the remaining 25 unloaders so that the entire compressor is put into operation. It will be noted that during this unloading action either from one end of the cylinder, or both ends of the cylinder a discharge of air from the 30 inter-cooler is prevented and it is maintained under the normal pressure so that there is no loss by reason of such discharge and on resumption of pumping no jar, or excessive heating. Current is conducted to the motor 35 through the lines 145 and a shunt 146 leads from this to an electro-magnet 147. A rheostat lever 148 operates over the contacts 149 in the usual manner and when current is fully on the lever 148 is held in position by 40 the magnet 147 and is automatically thrown to starting position by a spring 150 should the current fail in the magnet 147. This is the ordinary starting device and has the usual mounting 151.

45 A frame 152 is mounted on a standard 153 and this is carried by a floor plate 154 so as to properly adjust it to the mounting 151. Air is carried by the pipe 144 to the inlet 50 port 155 of a body 156 of a controlling device. The port 155 communicates with a vertical port 157 at the ends of which are the valve seats 158 and 159 controlled by valves 160 and 161 respectively. A stem 162 extends from the valve 161 and terminates in 55 a head 163. A spring 164 operates against said head. The spring and head are mounted in a shell 165, the lower shoulder 166 limiting the expansion of the spring. The shell 165 is slidingly mounted in the frame 152 and terminates with a cap 167. This cap is 60 in the path of a cam 168 on the end of the lever 148 and this cam is shaped to force the shell 165 downwardly to the limit of its movement when the lever 148 is in its final 65 position closing the circuit. In this posi-

tion it forces the valve 161 to its seat with the spring pressure of the spring 164. A stem 169 extends from the valve 160 and a spring 170 operates against the stem 169 and tends to close the valve 160. Pins 171 extend between the valves 161 and 160 so that as one is closed the other is necessarily open. The spring 170 is of less strength than the spring 164 so that as the valve 161 is forced downwardly the valve 160 is opened but as the cap 167 is released by the cam 168 the spring 170 is of sufficient strength to close the valve 160, at the same time opening the valve 161 and forcing the shell 165 upwardly. In the initial position at starting the valve 160 is closed and the valve 161 opened. A port 172 leads from the port 157 to the inlet end 173 of the body 156 and is connected by a pipe 174 with the receiver or pipe 77 so that this port is constantly under receiver pressure. With the lever 148 at starting position, therefore, receiver pressure passes by way of the port 157, the valve 160 being closed, and thence by the port 155 to the pipe 144 and into the exhaust sides of the regulator. If the receiver pressure is below the pre-determined pressure the exhaust valves in both regulators will be open and the inlet valves of these regulators closed. The receiver pressure, therefore, will pass by way of the exhaust valves into the pipes leading to the several unloaders and relief valves so that with the starting of the motor regardless of receiver pressure the compressor will be unloaded as the motor starts. As the motor builds up its speed and the starting lever is carried to its final position the cam with the last movement of the lever operates to reverse valves 160 and 161 closing the valve 161 and opening the valve 160. This immediately opens the exhaust sides of the regulator to the atmosphere by way of the port 175 which is connected by a discharge passage 176 with the discharge pipe 177 which may go to the atmosphere or to the intake of the compressor of any convenient point of discharge. If the receiver is below the pre-determined pressure then the inlet valves to the regulators will remain closed and full pumping will immediately begin or if the pressure is at an intermediate point one set of unloaders may be opening so that one end of the cylinders may start pumping. On the other hand if the receiver pressure is above the pre-determined pressure both inlet valves will be open and the cylinders as a whole will continue unloaded until the receiver pressure is reduced, the regulators operating in the normal manner. Broadly the starting mechanism just described forms the subject matter of application #519,166 filed by me Dec. 1st, 1921 electric motor load controlling devices.

With these inlet unloaders used in con-

70

75

80

nection with a relief valve the cylinders are exhausted down to practically atmospheric pressure in the final clearance. The relief valves are an advantage in the final unloading even where this device is used with a single compressor and is of peculiar advantage where the pressure is stepped up both for economy and saving as to the inter-cooler. The maintenance of the normal pressure in the intercooler during the unloading is desirable both for efficiency and smoothness of running and the elimination of heat in the loading up. The manner of unloading the cylinders makes the comparative pumping of the two cylinders always equal so that a comparatively constant pressure is maintained in the intercooler which may be arranged at the most desirable pressure.

It will be noted that the relief valve with its screw-threaded fitting as 48, Fig. 12, is screwed into the indicator opening of the compressor, such openings being usually standard equipment on compressors and this is inconvenient so far as indicator attachments are concerned. It will be noted, therefore, that the pilot valve is provided with a plug directly connected with the passage 49 and by the removal of this plug the indicator may be attached in approximately the same position arranged for it.

What I claim as new is:

1. In a pump, the combination of a low pressure cylinder; a high pressure cylinder; pistons in said cylinders pumping at both ends of said cylinders; unloaders for said cylinders, said unloaders operating to close the intakes of each end of said cylinders independently; and means controlling said unloaders to operate one unloader of the low pressure cylinder in unison with one unloader of the high pressure cylinder and independently of the other ends of said cylinders and to unload the remaining ends of said cylinders in unison subsequently to the unloading of the first-mentioned ends.
2. In a pump controlling mechanism, the combination of a compressing cylinder having an inlet and discharge; an unloader closing the inlet of the cylinder; a relief valve discharging the cylinder to a pressure below a discharge pressure; and pressure actuated means controlling said unloader and relief valve to actuate the same simultaneously.

3. In a pump controlling mechanism, the combination of a pump cylinder having an inlet and discharge; an unloader closing the inlet of the cylinder; a relief valve discharging the cylinder to a pressure below a discharge pressure comprising a valve; a loading means for the valve; and a pressure actuated motor releasing the loading means.
4. In a pump controlling mechanism, the

combination of a pump cylinder having an inlet and discharge; an unloader closing the inlet of the cylinder; a relief valve discharging the cylinder to a pressure below a discharge pressure comprising a valve; a spring holding the valve normally closed; and a fluid actuated pressure device releasing the valve from the pressure of the spring.

5. In a pump controlling mechanism, the combination of a pump cylinder having an inlet and discharge; an unloader closing the inlet of the cylinder; a relief valve discharging the cylinder to a pressure below a discharge pressure comprising a valve body; a valve in the body; a fluid pressure cylinder; a pressure pin acting on the valve to close the same; a piston acting on the pressure pin; and a counter-pressure spring acting on the pressure pin to close the valve.

6. In a pump controlling mechanism, the combination of a pump cylinder having an inlet and discharge; an unloader closing the inlet of the cylinder; a relief valve discharging the cylinder to a pressure below a discharge pressure comprising a valve body; a valve in the body; a gland fitting; a cylinder mounted on the gland fitting; a pressure pin extending through the gland fitting into engagement with the valve; a piston in the cylinder operating on the pin and a spring acting on the pin to close the valve.

7. In a pump controlling mechanism, the combination of a low pressure cylinder; a high pressure cylinder to which the low pressure cylinder discharges; an unloader closing the inlet for the low pressure cylinder; an unloader for the high pressure cylinder; and a relief valve for the low pressure cylinder discharging to a lower pressure than the discharge of said cylinder.

8. In a pump controlling mechanism, the combination of a low pressure cylinder; a high pressure cylinder to which the low pressure cylinder discharges, said cylinders having inlets and discharges; unloaders closing the inlets to said cylinders; and relief valves discharging from said cylinders at a pressure below the discharge pressure of said cylinders.

9. In a pump controlling mechanism, the combination of a low pressure cylinder; a high pressure cylinder to which the low pressure cylinder discharges; an unloader closing the inlet for the low pressure cylinder; an unloader for the high pressure cylinder; a relief valve for the low pressure cylinder discharging to a lower pressure than the discharge of said cylinder; and pressure-actuated means for controlling the relief valve and inlet unloader simultaneously.

- 6
10. In a pump controlling mechanism, the combination of a low pressure cylinder; a high pressure cylinder to which the low pressure cylinder discharges; an unloader closing the inlet for the low pressure cylinder; an unloader for the high pressure cylinder; a relief valve for the low pressure cylinder discharging to a lower pressure than the discharge of said cylinder; and pressure actuated means for actuating the unloaders and relief valve simultaneously. 70
11. In a pump controlling mechanism, the combination of a pump cylinder; a piston discharging at both ends of said cylinder; inlet unloaders for both ends of said cylinders; relief valves for both ends of said cylinders discharging to a pressure less than the discharge pressure; and means for unloading one end of said cylinder and actuating the relief valve at the same end of said cylinder independently of the unloader and relief valve at the opposite end of the cylinder. 75
12. In a pump controlling mechanism, the combination of a pump cylinder; a piston discharging at both ends of said cylinder; inlet unloaders for both ends of said cylinder; relief valves for both ends of said cylinder discharging to a pressure less than the discharge pressure; and means for unloading and actuating the relief valve at each end of the cylinder simultaneously and the valve and unloader at one end of the cylinder subsequently to the valve and unloader at the other end of the cylinder. 80
13. In a pump controlling mechanism, the combination of a low pressure cylinder; a high pressure cylinder to which the low pressure cylinder discharges, said cylinders having separate inlets to each end and discharges; unloaders closing the inlets to said cylinders; relief valves operating at each end of each cylinder to pressures less than the discharge pressure of said cylinders; and means actuating the unloader and relief valve at one end of the low pressure cylinders simultaneously with the unloader and relief valve at one end of the high pressure cylinder and independently of the action of the unloaders and relief valves at the opposite ends of said cylinders. 85
14. In a pump controlling mechanism, the combination of a pump having a low pressure cylinder and a high pressure cylinder; a receptacle between the cylinders receiving the discharge from the low pressure cylinder and discharging to the high pressure cylinder; and an unloading mechanism for said cylinders acting on the inlets of said cylinders closing the receptacle to the cylinders during the period the unloading mechanism is operating. 90
15. In a pump controlling mechanism, the combination of a low pressure pump; a high pressure pump; unloaders for said pumps; a motor driving said pumps; a controlling device controlling said motor; and pneumatically actuated means actuated by the controlling device controlling the unloaders on both pumps unloading the same at starting. 95
16. In a pump controlling mechanism, the combination of a low pressure pump; a high pressure pump, a motor driving said pumps; unloaders normally controlled by the pumped fluid operating on said pumps; a controlling device controlling said motor; and pneumatically actuated means actuated by the controlling device controlling the unloaders on the pumps unloading the same at starting independently of the pumped pressure. 100
17. In a pump controlling mechanism, the combination of a pump, a pump cylinder; a piston in the cylinder pumping at both ends of the cylinder; independent unloaders for each end of the cylinder; means for actuating said unloaders independently; a motor driving the pump; a controlling device for the motor; and means actuated by the controlling device controlling both unloaders to unload both ends of the cylinder at the starting of the pump. 105
18. In a pump controlling mechanism, the combination of a pump; a cylinder; a piston in the cylinder pumping at both ends of the cylinder; unloaders for both ends of the cylinder; means actuated by the pumped fluid for actuating said unloaders to unload said ends of the cylinder successively; a motor driving the pump; a controlling device for the motor; and means actuated by the controlling device for operating the unloaders at both ends of the cylinder and independently of the pressure of the pumped fluid for starting the motor. 110
19. In a pump controlling mechanism, the combination of a pump comprising a low pressure cylinder; a pump comprising a high pressure cylinder to which the low pressure cylinder discharges; pistons in said cylinder pumping at both ends of said cylinders; unloaders controlling the ends of both cylinders and operating independently on the ends of said cylinders; a motor driving said pumps; a controlling device for said motor; and means actuated by the controlling device for unloading both ends of both cylinders at the starting of the motor. 115
20. In a pump controlling mechanism, the combination of a pump comprising a low pressure cylinder; a pump comprising a high pressure cylinder to which the low pressure cylinder discharges; pistons in said cylinders pumping at both ends of said cylinders; unloaders for each end of each cylinder, the unloader at one end of each cylinder operating independently of the unloader at the opposite end of the cylinder; 120

- pressure actuated mechanism responsive to pumped fluid pressure actuating said unloaders; a motor driving the pumps; a controlling device for the motor; and means actuated by the controlling device for unloading all of said unloaders at the starting of the pump.
21. In a pump controlling mechanism, the combination of a pump comprising a low pressure cylinder; a pump comprising a high pressure cylinder to which the low pressure cylinder discharges; unloaders for said cylinders; means responsive to pumped pressure for normally controlling said unloaders; a motor driving said pumps; a controlling device for the motor; and pneumatically actuated means actuated by the controlling device unloading said pumps at the starting of the motor.
22. In a pump controlling mechanism, the combination of a pump; an unloader acting to unload the pump when subjected to pressure; a motor driving the pump; a controlling device for the motor; and means controlled by the device putting the unloader under pressure until the motor is started.
23. In a pump controlling mechanism, the combination of a pump; an unloader acting to unload the pump when subjected to pressure; a motor driving the pump; a controlling device for the motor; a regulator responding to pumped pressure normally controlling the unloader; and means controlled by the device putting the unloader under pressure until the motor is started.
24. In a pump controlling mechanism, the combination of a pump, an unloader acting to unload the pump when subjected to pressure; a motor driving the pump; a controlling device for the motor; a regulator responding to pumped pressure normally controlling the unloader; and means controlled by the device and acting through the regulator to put the unloader under pressure until the motor is started.
25. In a pump controlling mechanism, the combination of a pump; an unloader for said pump, said unloader acting when subjected to pressure; a regulator controlling the unloader having connections and inlet and exhaust valves therefor, the inlet valve normally controlling the pumped pressure acting on the unloader; a motor driving the pump; a motor controlling device; a starting load controller comprising pressure controlled inlet and exhaust valves; a pressure connection between the controller and the exhaust connection of the regulator; and means acting as the controlling device is actuated for actuating the controller to admit pressure to the exhaust connection with the controlling device in a position starting the motor.
26. In a pump controlling mechanism, the combination of a low pressure pump comprising a low pressure cylinder; a piston discharging at both ends of the cylinder; a high pressure pump to which the low pressure pump discharges comprising a cylinder; and a piston operating a pump at both ends of the cylinder; unloaders for each end of each cylinder; a regulator having inlet and exhaust connections and inlet and exhaust valves controlling the unloader of one end of a low pressure cylinder and one end of the high pressure cylinder; a regulator having inlet and exhaust connections and inlet and exhaust valves controlling the unloaders at the opposite ends of said cylinder, the second-mentioned regulator having its inlet leading from the first-mentioned regulator, the exhausts of said regulators being connected through a conduit with a load controller comprising inlet and exhaust valves; a motor driving said pumps; a controlling device for the motor; and means actuated by the controlling device actuating the controller to open the inlet valve thereof to deliver pressure to the exhaust connections of the regulators at the starting of the motor.
27. In a pump controlling mechanism, the combination of a cylinder having separate inlet passages; an unloader having separate passages communicating with the passages of the cylinder and a single inlet passage; and unloader controlling valves controlling the passages of the unloader.
28. In a pump controlling mechanism, the combination of a cylinder having separate inlet passages; an unloader having separate passages communicating with the passages of the cylinder and a single inlet passage; unloader controlling valves controlling the passages of the unloader; and means for controlling said unloader valves independently.
29. In a pump controlling mechanism, the combination of a cylinder having inlet passages adjacent to each other and with a surrounding joint face and a bridge face between the two passages; and an unloader having corresponding faces with separate passages therein leading to each passage of the cylinder.
30. In a pump controlling mechanism, the combination of a cylinder having inlet passages adjacent to each other and with a surrounding joint face and a bridge face between the two passages; and an unloader having corresponding faces with separate passages therein leading to each passage of the cylinder, the unloader having a single inlet passage.
31. In a pump controlling mechanism, the combination of a pump having a low pressure cylinder; a high pressure cylinder; a receptacle between the cylinders receiving the discharge from the low pressure cylinder and discharging to the high pressure

- cylinder; an unloading mechanism for the low pressure cylinder; an unloader for the high pressure cylinder working on the inlet side of the high pressure cylinder, said mechanisms maintaining the receptacle pressure normal during the period the unloading mechanism is acting; and a relief device for the high pressure cylinder relieving the pressure as it is unloaded.
32. In a pump controlling mechanism, the combination of a pump having a low pressure cylinder; a high pressure cylinder; a receptacle between the cylinders receiving the discharge from the low pressure cylinder and discharging to the high pressure cylinder; an unloading mechanism for the low pressure cylinder acting on the inlet of said cylinder; an unloading mechanism for the high pressure cylinder, said mechanisms maintaining the receptacle pressure normal during the period the unloading mechanism is acting; and a relief device for the low pressure cylinder acting as the cylinder is unloaded.
33. In a pump controlling mechanism the combination of a pump having a low pressure cylinder and a high pressure cylinder; a receptacle between the cylinders receiving the discharge from the low pressure cylinder and discharging to the high pressure cylinder; an unloading mechanism acting on the inlets of said cylinders for said cylinders maintaining the receptacle pressure normal during the period the unloading mechanism is acting; and relief devices for said cylinders acting on said cylinders as they are unloaded.
34. In a pump controlling mechanism, the combination of a pump having a low pressure cylinder and a high-pressure cylinder; a receptacle between the cylinders receiving the discharge from the low pressure cylinder and discharging to the high pressure cylinder; an unloading mechanism for the low pressure cylinder; an unloading mechanism for the high pressure cylinder acting on the inlet of said high pressure cylinder, said mechanisms closing the receptacle to the cylinders during the period the unloading mechanism is acting; and a relief device for the high pressure cylinder acting as said cylinder is unloaded.
35. In a pump controlling mechanism, the combination of a pump having a low pressure cylinder and a high pressure cylinder; a receptacle between the cylinders receiving the discharge from the low pressure cylinder and discharging to the high pressure cylinder; an unloading mechanism for the low pressure cylinder acting on the intake of the low pressure cylinder; an unloading mechanism for the high pressure cylinder, said mechanisms closing the receptacle to the cylinders during the period the unloading mechanism is operating; and a relief device for the low pressure cylinder acting on the cylinder as it is unloaded.
36. In a pump controlling mechanism, the combination of a pump having a low pressure cylinder and a high pressure cylinder; a receptacle between the cylinders receiving the discharge from the low pressure cylinder and discharging to the high pressure cylinder; an unloading mechanism acting on the inlets of said cylinders for said cylinders closing the receptacle to the cylinders during the period the unloading mechanism is operating; and relief devices for said cylinders acting as they are unloaded.

In testimony whereof I have hereunto set my hand.

RUDOLPH CONRADER.
